Attorney

UNITED STATES PATENT OFFICE.

EDWARD E. JUDD AND LOUIS MINNICK, OF KANSAS CITY, MISSOURI.

KNIFE AND SCISSORS SHARPENER.

Application filed September 23, 1922. Serial No. 590,133.

To all whom it may concern:

Be it known that we, EDWARD R. JUDD and LOUIS MINNICK, citizens of the United States, residing at Kansas City, in the county of 5 Jackson and State of Missouri, have invented certain new and useful Improvements in Knife and Scissors Sharpeners, of which the following is a specification.

Our invention relates to improvements in 10 knife and scissors sharpeners, and one object is to produce a simple device of this character which can be used by an unskilled person with good results.

Another object is to provide a sharpener 15 in which new abrading surfaces can be adjusted into the use from time to time as they wear away from use.

Another object is to provide suitable 20 guides for directing a knife or pair of scissors into proper relation with the abrading disks, so that practically anyone will be able to bring the object being sharpened into contact with said disks to the best advantage.

A further object is to provide a device of 25 this character which can be manufactured at relatively small cost and is not likely to get out of order.

With the above and other objects in view, 30 reference will now be had to the accompanying drawing, in which:

Fig. 1 is a front elevation of the device.

Fig. 2 is a rear elevation thereof.

Fig. 3 is a side elevation of the device.

Fig. 4 is a plan view of the device.

In carrying out the invention, we employ 35 a bracket 2, having a pair of rearwardly projecting arms 4 and 6, respectively, the arm 6 being provided with a thumb-screw 8, which coacts with the arm 4 in holding the 40 bracket 2 upon a support, such as a table, bench, etc.

10 designates an abrading disk journaled upon a screw 12 extending through the upper portion of the bracket 2 and secured at its 45 rear end by a nut 14, which may be tightened to hold the disk stationary, or loosened so that said disk may be rotated from time to time to bring a new cutting surface into contact with the object being sharpened. Said 50 disk 10 may be made of any suitable abrading material, as stone, steel, carborundum, etc.

15 designates a bifurcated guide for co-acting with the disk 10 in sharpening a pair

of scissors. The edges 17 of said guide 15 are beveled in order to allow the scissors blade A to be drawn at an angle across the disk 10, to give the proper edge to said scissors.

16 designates a V-shaped guide at one side 60 of the guide 15 and adapted to coact with the disk 10 in sharpening knives, etc.

18 designates a second abrading disk 65 mounted on a screw 20 secured by a nut 22. The screw 20 extends through a slot 24 in the bracket 2, so that the disk 18 can be moved closer to the disk 10 to take up wear.

26 designates a V-shaped guide in the opposite side of the bracket 2 containing the guide 16. Said guide 26 is adapted to coact 70 with the disk 18 in sharpening knives. The edges 27 and 29 of the grooves 16 and 26 are beveled to hold the knives in proper relation to the disks 10 and 18, respectively.

The operation is as follows: In sharpening 75 a pair of scissors, one blade is placed against one side of the guide 15 and then drawn back and forth across the disk 10 until sharpened, after which the other blade is sharpened in a like manner, the beveled edges 17 of the guide 15 holding the respective blades in proper relation to the disk 10. In sharpening a knife it may be placed in either the groove 16 or 26 and drawn back and forth across the respective disks 10 and 18, or said knife may be sharpened by drawing it back and forth between the peripheries of said disks 10 and 18, as indicated at B. If it is desired to give a fine or thin edge to the knife blade the two disks 10 and 18 are separated slightly by adjusting the disk 18 slightly away from the disk 10, which may be accomplished by loosening the nut 22 and sliding the screw 20 in the groove 24. As the disks 10 and 18 become 85 worn from use their respective screws 12 and 20 may be loosened, thus allowing said disks to be rotated to bring new sharpening surfaces into position, after which they are again held stationary by tightening said 90 screws 12 and 20.

While we have shown the preferred embodiment of our invention, we reserve the right to make such changes in the construction, combination and arrangement of parts 105 as properly fall within the spirit and scope of the appended claim.

Having thus described our invention, what

we claim and desire to secure by Letters Patent, is:

In a device of the character described, a bracket provided with means for securing it to a support, a pair of abrading disks associated with said bracket, V-shaped guides formed in opposite sides of the bracket for supporting knife blades in position to be sharpened against the periphery of said disks, and a bifurcated guide on the bracket

for holding scissor blades in position to be sharpened against the periphery of one of the disks.

In testimony whereof we affix our signatures, in the presence of two witnesses.

EDWARD R. JUDD.
LOUIS MINNICK.
